INDEFORMABLE BOBBIN FOR SPINNING
ARTIFICIAL YARNS

Aldo Bazzocchi, Milan, Italy

Application December 28, 1932, Serial No. 649,201
In Italy January 19, 1932

7 Claims. (Cl. 18—8)

When spinning artificial yarns on the bobbin system, the bobbins constitute the members on which the yarn is wound in normally wet condition.

5 The bobbins are generally made of acid-proof metal, for instance aluminium, and have the shape of a cylinder with reinforced edges and with the walls perforated with thickly set holes of but a few millimeters diameter.

10 The yarn is wound in wet condition on the said bobbins and is then subjected, in wound condition, to a set of treatments intended to wash, desulfurate, bleach etc. the yarn. All such treatments

15 are wet treatments, so that the bobbins finally must be passed into hot air dryers where the yarn is freed from the moisture and thus made ready for the following twisting, reeling, etc.

It is well known that, on drying, the artificial 20 yarn, for instance regenerated viscose yarn, tends to shorten and thus it happens that, on the conventional bobbins, the yarn layers adjacent to the body of the bobbin cannot shorten because the bobbin is rigid, whereas the outer layers can 25 shorten inasmuch as the underlying yarn-layers constitute a soft and compressible mass.

The difference in the behavior of the inner and of the outer layers during the drying process is a cause of differences in the characteristics of the 30 yarn itself, the latter differences being a source of serious defects in weaving. In order to avoid these defects, the yarn is generally made up in hanks and then wetted and dried again, in order that any portion of artificial yarn that has not contracted freely during the drying of the bobbin 35 may contract then and become uniform in its elongation and tenacity characteristics. Such a method is expensive inasmuch as it involves a greater number of operations and a greater number of machines, and impairs the quality of the 40 yarn.

The subject matter of the present invention is a deformable bobbin made of several sections 45 characterized by the fact that, whereas it remains rigid during the winding and wet treatments of the yarn, it is rendered deformable during the drying process by simply disengaging a hook.

50 The degree of deformability is, of course properly designed so as to allow the yarn to freely and uniformly contract as well in the inner as in the outer layers. In other words, if it is first determined that on drying the contraction of 55 the yarn is about 8%, the bobbin should be de-

formable as much as will suffice to allow its circumference to decrease by 8%.

In this manner no differences will exist in the characteristics of the inner and of the outer layers of the yarn and the weaving defects will therefore be avoided without resorting to further successive operations.

The accompanying drawings illustrate two embodiments of the deformable bobbin according to the invention merely by way of example, it being understood that the examples do not at all limit the scope of the invention.

In the drawings:

Fig. 1 is a longitudinal section showing the first 15 type of deformable bobbin.

Fig. 2 shows the same bobbin in cross section.

Fig. 3 is a longitudinal section showing the second type of deformable bobbin.

Fig. 4 shows the bobbin according to Fig. 3 in 20 cross section.

The bobbin according to Figs. 1 and 2 is longitudinally divided into three sections 1—2—3. Section 1 is connected to section 3 by the hinges 4.

Section 2 is connected to section 3 by the 25 hinges 5.

Sections 3 and 1 are secured to one another by means of the elongated rings 6 which engage the hooks 8. The said rings are actuated by the levers 7 pivoting about in the hinges 5.

When the rings 6 are engaged in the hooks 8, the complex built up of the three bobbin sections is rigid, since it is constituted by a hinged triangle. Under these definitely restricted conditions the bobbin will receive the yarn 9 and the ends of body of the wound yarn will rest on two elastic bands 10, 10, preferably of india rubber, provided at the bobbin ends, these bands having the purpose of preventing the liquid from passing through the discontinuities or gaps resulting at the edges which are not covered by the yarn, when, during the moistening, the vacuum system is used.

After completion of the winding and subsequent wet-treatments of the yarn, the levers 7 should be raised before the bobbin is laid in the drying room. This will disengage the rings 6 from the hooks 8, and the section 2 which was formerly held between the edges of sections 1 50 and 3 by a portion of the ring 6 and by a hinge 11 pivoting at 5, will be allowed to tilt inwardly and thus permit the sections 1 and 3, which are hinged together, to move towards each other.

The bobbin will thus take up an oval form, the 55

perimeter of which is smaller than the original circumference by the amount of the width of section 2 which has tilted inwardly.

The said amount is determined by the shortening which the yarn experiences in drying.

In practice it has also been found that the bobbin may be made also in two sections only, the hooking system being thus simplified and rendered more practical. The object of allowing the bobbin to decrease in circumference under the stress of the yarn as it contracts in drying, is reached in any case inasmuch as the bobbin, owing to its cylindrical shape, is sufficiently elastic since, under a minimum portion of the contraction stress of the yarn, the two edges which prior to the drying opposed themselves to the tiltable gate being opened, approach one another till they come into contact when, during the drying process, the said gate has been lowered in advance.

Referring now to Figs. 3 and 4, the bobbin is longitudinally divided into two sections 1 and 2 connected to each other by the hinges 3. The sections 1 and 2 are secured together by extensions 25 of the hinges 3, these extensions being in the shape of handles 4 and fitted with a hole for engagement with the pins 5 provided on the section 2.

When the sections 1 and 2 are secured together, the bobbin formed by them is rigid. Under 30 these rigid conditions the bobbin receives the yarn 6, and the ends of the body of the wound yarn rest on the marginal elastic bands or sheaths 10 provided at the ends of the section 1, these bands having the purpose of preventing the liquids from 35 passing through the gaps or fissures resulting at the edges which are not covered by the yarn, when, during the moistening, the vacuum system is used.

On completion of the winding and of the following wet-treatments of the yarn, prior to laying the bobbin in the drying room of the two handle-shaped extensions 4 are pushed inwardly, thereby releasing the section 1 from section 2. Under the contraction stress exerted by the 45 yarn in drying, the opposite edges of section 2 will move nearer due to the elasticity of the bobbin and the bobbin will take an oval form, the perimeter of which will be smaller than the original extreme circumference by an amount equal 50 to section 1 width that has been tilted inwardly.

This width of the section 1 is determined by the amount of shortening undergone by the yarn in drying.

Having now particularly described and ascertained the nature of my said invention and in what manner the same is to be performed, I declare that what I claim is:—

1. A bobbin for winding artificial yarn thereupon, comprising the combination of arcuate members provided with hinge means interconnecting two abutting ends thereof, at least one pair of abutting ends being separable and one of said members being outwardly swingable upon the hinge means into an extreme operative position wherein said members together form an annular rigid bobbin body for wet treatment of the yarn, and which one swingable member is also swingable inwardly from said operative position so as to leave a gap in the periphery of the bobbin body and allow partial collapse thereof to at least the extent corresponding to the shrinkage of the yarn during drying treatment thereof, and covering means for the fissures beyond the yarn at both ends of the bobbin between the 65 bobbin members in order to prevent liquids from

passing through the fissures in the operative position of said bobbin members.

2. A bobbin for winding artificial yarn thereupon, comprising the combination of arcuate and perforate plate members provided with hinge means interconnecting two abutting ends thereof, at least one pair of abutting ends being separable and one of said members being outwardly swingable upon the hinge means into an extreme operative position wherein said members together 10 form an annular rigid bobbin body for wet treatment of the yarn, which one swingable member is also swingable inwardly from said operative position so as to leave a gap in the periphery of the bobbin body and allow partial collapse thereof to at least the extent corresponding to the shrinkage of the yarn during drying treatment thereof, and a pair of flexible annular end sheaths disposed on the end margins of the bobbin body and serving as shields covering the exposed perforated 15 areas and the fissures corresponding to the connections in the gap between the members of said body beyond the yarn windings in order to prevent any liquid from passing idly through said exposed perforated areas and the fissures during 20 wet treatment of the yarn under pressure or vacuum.

3. A deformable bobbin according to claim 1, wherein the hinge means are disposed upon the bobbin members solely within the annular outline thereof in order to avoid projections and obstructions on said bobbin beyond said outline and also to cause the swingable member to remain within said outline in all positions and be swingable solely inward from and outward to the 25 same outline into extreme positions.

4. A deformable bobbin according to claim 1, wherein the bobbin has two arcuate members aside from the swingable arcuate member, which two members are provided with intermediate 30 hinge means connecting the two abutting ends of same together so that when said swingable member is swung inward into collapsed position, said two members may be collapsed to a limited extent tending to close the gap between 35 them normally occupied by the swingable member when in operative position, while the yarn and the covering means for the fissures remain in situ in collapsed positions of said members.

5. A deformable bobbin according to claim 1, 50 wherein the swingable bobbin member is limited to swing solely inward from and outward to the normal annular outline of the bobbin, and the other member is inherently deformable to a limited extent tending thus to bring the ends thereof together and close the gap normally occupied by the swingable member when in operative position, in order to decrease the perimeter of the bobbin at will, while the yarn and the covering 55 means for the fissures remain in situ in collapsed positions of said members.

6. A deformable bobbin according to claim 2, which is provided with locking means hinged to at least one of the arcuate bobbin members within the annular outline of the bobbin body for locking the bobbin members together to form a rigid unit in assembled operative condition.

7. A deformable bobbin according to claim 2, which is provided with locking means directly bridging the gap occupied by the swingable member, hinged to one of the arcuate bobbin members and disposed beneath the latter and locking the bobbin members together to form a rigid unit in operative assembled position thereof.
